UNITED STATES PATENT OFFICE

HORACE C. WRIGHT, OF CHICAGO, ILLINOIS, ASSIGNOR TO CHICAGO FLEXIBLE SHAFT COMPANY, OF CHICAGO, ILLINOIS, A CORPORATION OF ILLINOIS

ADJUSTABLE NOZZLE

Application filed June 10, 1931. Serial No. 543,437.

This invention relates to sprinklers and has particular reference to adjustable nozzles forming a part thereof and serving to produce a proper flow of liquid from the 5 sprinkler.

It is desirable in sprinklers of the type designed primarily for use in sprinkling lawns and the like, to make the nozzle as sturdy and as free from operating difficulties as possible, compatible with proper distribution of the water. Another factor in their design is cost of manufacture. A major difficulty with those of the prior art is the fact that they are so designed that plugging or stop- 10 page of the orifice is apt to occur under certain conditions of operation. The same features of design tend to reduce the velocity of the water emerging from the nozzle so that the area covered by the sprinkler is considerably less than that normally possible. 15 These devices have also been comparatively complicated, easily broken, and expensive to manufacture.

I have aimed to provide a nozzle having 20 a novel arrangement of parts producing improved means for adjusting the flow of liquid therefrom.

Another object of the invention is the provision of a nozzle having a minimum number 25 of parts each of which may be manufactured by economical forming operations.

A further object of the invention is the provision of a spray nozzle having improved means for distributing the water flowing 30 therethrough.

Other objects and attendant advantages will become apparent to those skilled in the art from the following description and the accompanying drawing in which—

40 Figure 1 is a side elevation of a lawn sprinkler embodying my invention;

Fig. 2 is a longitudinal section through one of the spray nozzles;

Fig. 3 is a section on the line 3—3 of Fig. 45 2, and

Fig. 4 is a top view of my improved nozzle.

While it will be understood that my invention is not limited to use with a lawn sprinkler, I have shown it in the drawing 50 as applied to a lawn sprinkler having a

sprinkler base 6 provided with means 7 for connecting the flexible hose or other water conducting means. A tube 8 is rotatably secured to the upper end of the base 6 and is provided with radial nozzle carrying arms 9 and 11 through which water or other liquid is conducted to opposed nozzles designated generally by the numerals 12 and 13. The nozzles 12 and 13 are connected to the outer ends of the arms 9 and 11 through threaded nipples 14 and 15 which also serve to conduct the water from the arms into the nozzles, the upper ends of the nipples engaging the threaded openings 16 in the nozzle body 17.

Each of the nozzles 12 and 13 consists of 55 a body portion 17 having angularly positioned connecting chambers 18 and 19, the chamber 18 serving to receive the water from the nipple 14 or 15. A tubular valve member 21, one end 22 of which has an outer 60 diameter such that it will be closely received within the chamber 19 is positioned in the latter chamber. The outer end 23 of the member 21 is of substantially smaller diameter both internally and externally than the portion 22 thereof, such as to provide a shoulder 24 on the outer side and a constriction 25 on the inner side. A knurled head portion 26 is positioned around the outer side of the portion 23 at one end of the member 21 and is advantageously secured thereto by being tightly pressed thereon as shown at 27. A collar 28 is rotatably and slidably positioned around the portion 23 between the shoulder 24 and the head portion 26 and is 65 provided with an inwardly sloping face 29 opposite the shoulder 24. A backing member 31 of leather or other suitable material is positioned between the shoulder 24 and the sloping face 29 and is adapted to be 70 compressed between the shoulder and the face and be forced against the walls of the chamber 19 to prevent the passage of liquid along the walls.

The valve chamber 22 is provided with an 75 opening 32 adapted, when the valve member is in its completely open position to form a continuation of the chamber 18 as shown in Figs. 2 and 3. This opening permits the water or other liquid to pass from the cham- 80

ber 18 through the opening 32 and out through the end 23 of the center 22. By manual rotation of the head 26 the opening 32 may be moved either wholly or partially out of coincidence with the chamber 18, thereby varying the amount of liquid discharged from the nozzle and the character of the discharge as will presently be more fully explained. A groove or other mark 33 is positioned on the body portion 17 and a groove 34 is positioned on the head member 26 to indicate the position of the opening 32 with respect to the chamber 18. Thus, in the drawing these indicating grooves are so positioned that when in coincidence the opening 32 is completely out of registration with the chamber 18 so that no water will flow from the nozzle. Upon rotation of the head 26 in either direction the opening 32 will be progressively brought into registration with the chamber 18 until it reaches complete registration as shown in Fig. 3.

It will be seen that the device consists of only five parts all of which may be made by low cost machining operations. These are the body member 17, the valve member 22, the head member 26, the collar 28, and the packing 31. The device is also very easily assembled by inserting the sleeve 22 within the chamber 19 of the body 17, placing the packing member 31 and the collar 28 over the end 23 of the valve member and forcing the head member 26 into position on the valve member. When the head member is brought into position the backing member 31 and the collar 28 are forced against the shoulder 24 rendering the joint liquid tight. In addition the collar 28 is placed firmly into the body 17 thereby serving to hold the valve member 22 in its proper position within the body member. The head 26 thus serves during the assembling operations to force the collar 28 into the body 17 by means of the face 35, the face 35 also serving as a stop by contact with the end 36 of the body 17. In this manner a nozzle is formed at a comparatively small cost because of the simplicity of its manufacture and its ease of assembly.

No supplementary means are necessary in order to produce the scattering effect desired of such a nozzle. For this reason it is not necessary to interpose devices in the stream of water to produce a spraying effect for as the opening 22 is moved nearly out of registration with the chamber 18 only a relatively small amount of water passes into the valve member 22. This water, however, enters at sufficient velocity to be carried rapidly out of the end 23 of the valve member, and its introduction at a small angle with respect to the valve member, combined with the constriction 25 serves to give this small amount of water such a movement that it will emerge from the end of the nozzle

in the form of small droplets. As the opening 32 is brought more nearly into registration with the chamber 18 the size of these droplets increases, until when the opening is in complete registration, a full stream of water will emerge from the nozzle. Because of this construction the nozzle does not have the usual tendency to clog since there is nothing within the valve member 22 against which particles of solid matter may lodge. Another reason is the trouble free operation of this device, the fact that there are no parts requiring delicate adjustment or no parts susceptible of being laterally bent or broken during the service of the device.

While I have thus described and illustrated a specific embodiment of my invention I am aware that numerous alterations and changes may be made therein without materially departing from the spirit or scope of my invention and I do not wish to be limited except as required by the prior art and the scope of the appended claims, in which—

I claim:

1. An adjustable nozzle comprising a body having converging chambers, a tubular valve member rotatably positioned in one of said chambers, having an opening positioned to be brought into registration with the point of convergence of said chambers by rotation of said member and an open outer discharge end of smaller inside and outside diameter than the remainder of said valve member providing a shoulder on the outer side of said member, a collar rotatably positioned on said member pressed into said chamber, a packing member on said valve member between said collar and said shoulder, and a knurled member secured to the outer end of said valve member for manual rotation thereof to vary the relative position of said valve member and said body to control the flow of liquid therefrom.

2. An adjustable spray nozzle comprising a body having a valve chamber provided with a closed and an open end, and a second chamber intersecting said valve chamber intermediate its ends having an open end adapted to receive liquid and an end opening into said valve chamber, a cylindrical valve member rotatably positioned in said valve chamber, said valve member comprising an inner portion of the outside diameter of which is substantially the same as the inside diameter of said valve chamber, and an outer portion of substantially smaller inside and outside diameter to provide a shoulder on said valve member, a space between the walls of said chamber and said valve member and form a constriction on the inside thereof, said first mentioned portion having an opening positioned to be brought into and out of registration with the end of said second chamber by rotation of said valve member to admit fluid

into said valve member, a collar in the space between said last mentioned portion and the walls of said chamber, having fixed bearing contact with said walls, rotatable bearing contact with said valve member, and a packing member pressed between said shoulder and said collar to prevent leakage of liquid around said valve member, and means for rotating said valve member to control the flow of liquid therefrom.

3. An adjustable spray nozzle comprising a valve chamber, a tubular valve member rotatably positioned in said chamber having a cylindrical inner surface of two different diameters, that of smaller diameter terminating in a discharge opening, and a sloping surface connecting the surfaces of different diameters, means for conducting liquid into said valve member at an obtuse angle with respect to the longitudinal axis of the discharge end of said valve member in a position to impinge against the inner surface of larger diameter at a point closely adjacent to said sloping surface, whereby to impart particular flow characteristics to said liquid, and means for regulating the fluid entering said valve member.

4. An adjustable spray nozzle comprising a body having a cylindrical valve chamber open at one end, a tubular valve member rotatably inserted in the open end of said chamber, means secured to the outer end of said valve member for manually rotating the same, said valve member projecting beyond said body only such distance as required for the attachment of said means, said valve member having a bore of larger diameter at the inner end thereof, a bore of smaller diameter at the outer end thereof forming an orifice, and a converging bore connecting said first mentioned bore, means for conducting liquid to said valve member at an obtuse angle with respect to the discharge end thereof in a position to impinge against the bore of larger diameter closely adjacent to said converging bore, said valve member having an opening adapted to register with said means upon rotation of the former, whereby the liquid is conducted into said valve member in a position and direction to impart desired flow characteristics to the liquid as it immerses from said orifice.

In witness of the foregoing I affix my signature.

HORACE C. WRIGHT.
